James Warren Stitt, Berkeley, Calif., assignor to Chester H. Ristenpart, San Francisco, Calif.

Application June 30, 1947, Serial No. 140,014

Term of patent 3½ years

(Cl. D33—7)

To all whom it may concern:

Be it known that I, James Warren Stitt, a citizen of the United States, residing at 2338 Ashby Avenue, in the county of Contra Costa, Berkeley, and State of California, have invented a new, original, and ornamental Design for Desks, of which the following is a specification, reference being had to the accompanying drawing, forming part thereof.

Fig. 1 is a perspective view of a desk, showing my new design.

Fig. 2 is a reduced size perspective view of the desk of Fig. 1 as the same is seen from the side opposite that shown in Fig. 1.

Fig. 3 is a reduced size end view of the desk of Fig. 1 as seen from the right side thereof.

Fig. 4 is a reduced size top plan view of the desk of Fig. 1.

Fig. 5 is an end view of the desk of Fig. 1, on a reduced scale and as seen from the left side thereof.

I claim:

The ornamental design for a desk, as shown.

JAMES WARREN STITT.
